UNITED STATES PATENT OFFICE.

HARVEY FELDMEIER, OF LITTLE FALLS, AND CHARLES F. WRAY, OF ROCHESTER, NEW YORK, ASSIGNEES TO D. H. BURRELL & CO., INC., OF LITTLE FALLS, NEW YORK, A CORPORATION OF NEW YORK.

DESIGN FOR A VALVE.

Application filed June 8, 1927. Serial No. 22,369. Term of patent 7 years.

To all whom it may concern:

Be it known that we, HARVEY FELDMEIER and CHARLES F. WRAY, both citizens of the United States of America, residing at Little Falls, county of Herkimer, and State of New York, and Rochester, county of Monroe, and State of New York, respectively, have invented a new, original, and ornamental Design for a Valve, of which the following is a specification, reference being had to the accompanying drawing, forming a part thereof.

Figure 1 is a side elevation of a valve showing our new design;
Figure 2 is an end elevation, and
Figure 3 is a plan view.

We claim:
The ornamental design for a valve, as shown.

HARVEY FELDMEIER.
CHARLES F. WRAY.
